UNITED STATES PATENT OFFICE.

JOHN PICCO, OF NEW YORK, N. Y.

LIFE-SAVING APPARATUS.

Application filed May 23, 1928. Serial No. 279,986.

This invention relates generally to life saving apparatus and the improvements are directed to novel means for supplying fresh air to the occupants of a life boat regardless of the position thereof in the water.

Primarily, the object of the present invention is to provide a life boat, having an inclosed hull, with a tubular member adapted to communicate between the interior of said hull and the atmosphere irrespective of the position of said hull.

Another object is to provide means for opening and closing the respective ends of said tubular member so that a supply of air may be had within the hull of the life boat.

Another object is the provision of means responsive to the movements of the life boat to permit the entrance of air for the occupants' consumption while preventing water from entering.

Still another object of the invention is to provide means whereby any accidental discharge of water in the tubular member may be readily removed.

As will presently appear the invention is adapted to be associated with my improved life saving apparatus, described and claimed in my allowed application Serial No. 93,168, filed March 8, 1926, said apparatus including an inclosed hull associated with certain righting devices. In the instant invention means is provided for supplying fresh air to the occupants of the craft regardless of the position thereof,—that is, even a complete capsizing of the craft cannot endanger the lives of the passengers since the very movements of the hull are communicated to the air-supply means to the end that an abundance of fresh air may be present in the hull were the same in a complete capsized position.

With these objects in view, together with others which will appear as the description proceeds, the invention resides in the novel formation, combination, and arrangement of parts, all as will be described more fully hereinafter, illustrated in the drawings, and particularly pointed out in the claims.

In said drawings:

Figure 1 is a central, longitudinal sectional view of my improved life boat, partly in elevation, and illustrating my invention associated therewith.

Fig. 2 is a transverse sectional view, taken substantially on the line 2—2 of Fig. 1.

Fig. 3 is a view like unto Fig. 2, but illustrating the craft in a complete capsized condi-

tion with the air-supply means communicating with the atmosphere.

Fig. 4 is a central longitudinal sectional view of my novel form of air supply means, somewhat enlarged, and detached from the hull of the life boat.

Fig. 5 is a transverse sectional view taken on the line 5—5 of Fig. 4, depicting the closure means in close position; and

Fig. 6 is a modified form of air-supply means operable in response to the varying movements of the hull; and

Fig. 7 is another form of valve element.

Referring now more in detail to the accompanying drawings, wherein like characters of reference denote similar parts throughout the several views, let 10 represent the hull of the life-boat of suitable stability and staunchness to withstand the abnormal strains attending its use, the same being provided with a deck 11, closing the hull with the exception of the hatch 12 by which the passengers may enter and leave. Said hatch 12 is closed by a closure 13 and attached thereto by any well-known means.

The interior of the hull 10 is provided with suitable conveniences to lighten the attending privations of the refugees, and includes bunks 14 and 15, each being provided with straps, as indicated at 16, to prevent undue jarring of the passengers during the extreme movements of the boat. Means for propelling the craft is provided in the form of a manually-operable crank 17 and a pulley 18 to which any suitable motive power may be applied, the rotation of the propeller shaft 19 being of course communicated to the wheel 20 located exteriorly of the hull. The course of the craft is guided by means of a rudder 21 operated by the steering wheel 22. The other details of the life-boat are quite similar to that disclosed in my Patent No. 1,683,409, dated September 4, 1928, and includes the lifting rings 23 and 24 and righting device denoted generally at 25. However, the air-supply means noted in said patent has been improved and will now be presented in detail.

Said air-supply means comprises a plurality of tubular members 26, preferably arranged vertically with respect to said hull 10 and each having its ends extending beyond the deck 11 and the bottom or keel of the former.

Each of said tubular members 26 is provided with an opening 27, (see Fig. 4), arranged intermediate the ends thereof, suitable closure means 28 being provided, bear-

ing a gasket 29, to tightly close said opening in the event water should enter said members. Said closure means 28 is preferably hingedly disposed, as indicated at 30 and is provided 5 with a latch 31 to fasten the same in tight arrangement. It will be noted on inspection of said Fig. 4 that both the ends of said tubular members are flared, as shown at 32 and 33, the internal contour of each conforming 10 to float-like valves 34 and 35 arranged at the extremities of a reciprocatory member 36, the latter being longer than the tubular members as will presently appear.

When the craft is in its normal position the 15 lower ends of the tubular members will be beneath the surface of the water and in consequence the pressure exerted on the valves 35 will cause an intimate contact between itself and the flared ends 33 and hence the tight 20 joint secured precludes the danger of water entering the tubular members. In view of the greater length of said reciprocatory member 36, the other valves 34 are unseated from the flares 32 and naturally air may enter 25 therethrough and pass through the openings 27 to the interior of the hull upon manipulation of the closure means 28. However, it becomes necessary to consider another factor in the use of a life-boat, and that is the substantial capsizing of the same, thus cutting 30 off the air supply and ultimately smothering the occupants of the boat. Accordingly, reference is had to Fig. 3 wherein the diagrammatic showing of the hull, illustrates the same 35 in a complete capsized condition and in this instance it will be observed that the valve 34 now cooperates with the flare 32 to close this submerged end of the tubular members while valve 35 is elevated to permit the entrance of air to the interior of the hull as aforesaid.

While the pressure of the water closes the 40 particular valve submerged therein, it will be readily understood upon inspection of Fig. 4, that a rocking of the craft beyond an arc of 45 ninety degrees would free both ends from the water and in consequence, gravity would operate the valves when the same are out of the water, but as soon as either end of the tubular members enters the water the pressure aforesaid brings about the condition necessary to 50 supply fresh air to the interior of the hull.

In practice said openings 27 will be positioned above the normal water-line of the 55 craft and in the event water should enter the tubular members it may be readily removed by pumping or the like. But in any event so long as the water-line in the bottom portion of the tubular members does not rise above the openings no material damage will accrue 60 since a clear passage is defined between the interior of the hull and the atmosphere by way of the openings 27 and the open ends of the said tubular members.

In Fig. 6 there is shown a form of tubular 65 member 37, having its open ends extending

beyond the deck and bottom of the craft, the same being provided with the usual opening and closure means, but the reciprocatory member and its attached valves are not used. In this particular instance the opening 27 is 70 located to be above the water-line of the vessel irrespective of the position thereof and hence the presence of water in the end submerged will not interfere with the passage of air from one end of the tubular member to 75 the interior of the hull.

In Fig. 7 a modified form of valve 38 is shown, the same including a nipple 39 for attachment to a reciprocatory member 36, the lower sides thereof being tapered downwardly as indicated at 40, to present flat sides 80 adapted to contact similar formed flares carried by said reciprocatory member.

From the foregoing it is apparent I have developed a life-boat including air-supply 85 means adapted to operate regardless of the position of the boat and in view of the gravitation reciprocation of the member 36 the pumping action of the valves, when out of the water will tend to expel foul air from the 90 hull.

Having thus fully described my invention, I hereby reserve the benefit of all changes in form, arrangement, order, or use of parts, as it is evident that many minor changes may 95 be made therein without departing from the spirit of the invention or the scope of the following claims:

1. In combination with a life boat having an inclosed hull, a tubular member associated therewith and having both its ends extending beyond the hull and means responsive to the turning of said hull for closing one end of said tubular member.

2. In combination with a life boat having an inclosed hull, a tubular member associated therewith and having its ends extending beyond the hull and reciprocatory means responsive to the turning of said hull for closing one end of said tubular member.

3. In combination with a life boat having an inclosed hull, a tubular member arranged vertically therein and having its ends extending beyond the hull and reciprocatory means responsive to the turning of said hull for closing one end of said tubular member.

4. In combination with a life boat having an inclosed hull, a tubular member associated therewith and having its ends extending beyond the hull, reciprocatory means responsive to the turning of said hull for closing one end of said tubular member and closure means adapted to establish communication between the open end of said tubular member and the interior of the hull.

5. In combination with a life boat having an inclosed hull, a tubular member associated therewith and having its ends extending beyond the hull, a reciprocatory member arranged within said tubular member, means

positioned at both ends of said reciprocatory member and adapted to close one end of said tubular member upon capsizing of said hull and closure means operable to establish communication between the interior of the hull and the open end of said tubular member.

6. In combination with a life boat having an inclosed hull, a tubular member associated therewith and extending beyond the exterior 10 of said hull, the ends of said member being flared, a reciprocatory member positioned within said tubular member, valve means carried by both ends of said reciprocatory member and adapted to normally close one end of said tubular member, said reciprocatory member being subjected to the movements of the

hull to close the other end of said tubular member upon capsizing of the latter and closure operable to establish communication between the interior of the hull and the open 20 end of said tubular member.

7. In a life saving apparatus embodying an inclosed hull, a tubular member having its ends extending beyond the exterior thereof, means responsive to the movements of the hull 25 to close one end of said tubular member when the hull is in a substantially capsized condition and means operable to establish communication between the open end of said tubular member and the interior of the hull. 30

In testimony whereof I affix my signature.
JOHN PICCO.
